UNITED STATES PATENT OFFICE.

CONSTANTIN F. GRETZMACHER, OF CHESTER, ILLINOIS.

ADJUSTABLE MOLD OR FORM FOR CONCRETE CISTERNS CURBS.

Application filed July 24, 1924. Serial No. 727,939.

To all whom it may concern:

Be it known that I, CONSTANTIN F. GRETZMACHER, a citizen of the United States, residing in the city of Chester, in the State 5 of Illinois, have invented a certain new and useful Improvement in an Adjustable Mold or Form for Concrete Cistern Curbs, of which the following is a full, clear, and exact specification.

10 My invention refers to a mold, or form, for making concrete cistern curbs, and especially to a collapsible, adjustable form.

One object of my invention is to provide 15 a collapsible form, or mold, which may be easily transported and readily set up and adjusted for making curbs for cisterns, wells, or other reservoirs for holding liquids.

Another object of my invention is the production of a curb, or form, to be used in 20 combination with chain or bucket pumps that may be readily adjusted to different sizes of chain or bucket pumps and, also, readily adjusted to suit cisterns, or other liquid reservoirs, where the openings are of 25 various sizes.

A still further object of my invention is to provide a mold, or form, for cistern curbs that will effectively prevent insects, reptiles, or small quadrupeds from being precipitated 30 into said reservoirs and to make it difficult or impossible for them to enter said reservoirs in quest of water.

Still further objects and advantages of 35 my invention will be apparent from the more detailed description which is to follow.

Referring now to the drawings made a part of this specification:

Fig. I is a perspective view of a cistern curb together with its cover.

40 Fig. II is a sectional side elevation, showing the arrangement of the pump.

Fig. III is a longitudinal cross-section through the wheel opening.

45 Fig. IV is a cross-section at 4—4 in Fig. III.

Fig. V is a longitudinal cross-section of the body of the curb.

Fig. VI is a cross-section of the same at 6—6 in Fig. V.

50 Fig. VII is a cross-section of the cover of my curb form.

Fig. VIII is a cross-section at 8—8 in Fig. VII.

55 In sections of the country where natural sources of water supply are absent, or

limited, it is customary to excavate a reservoir in the ground and wall up same with brick or stone or concrete in such a manner that it becomes water-tight. The water precipitated on houses, barns and other 60 buildings during the winter months is conducted by means of eave troughs and conductor pipes to these excavated reservoirs and preserved for use throughout the year.

In order that the water may be kept sweet 65 and sanitary and fit for household and kitchen use, it is necessary that these reservoirs, usually designated as cisterns, be completely covered to prevent the accumulation of dirt and other foreign matter and, also, 70 prevent insects, reptiles and small quadrupeds from gaining ingress thereto in quest of water.

If a wooden platform is used, the timber 75 soon rots away and makes it an easy matter for insects, reptiles and small quadrupeds to gain access thereto, and thus the water is contaminated and made unfit for use.

For these reasons of late years cisterns 80 have been covered either by stone or concrete slabs. As it is necessary to have an opening for the purpose of drawing water therefrom, all of the covers are provided with openings but not of a uniform or standard size, hence if a curb, by which is meant the 85 upright support of a chain or bucket pump, is to serve the purpose of preventing insects and reptiles from having access thereto, it must securely cover the hole or opening already made, which as stated above are of 90 various sizes, that is to say no standard size hole has been adopted.

It is, therefore, desirable that a form, 95 which is to be used for making curbs to suit different size openings, have some means of adjustment by which these various size openings can be securely covered.

It is not only necessary that the cisterns be made inaccessible to insects and reptiles, but they must, also, be open to the atmosphere in order that the water may be aerated by natural means, otherwise it would become stagnant and unfit for use.

It will be readily understood that if each cistern curb had to be built by making a 100 special form for packing the concrete, the expense would be greatly increased, even prohibitive.

I have, therefore, designed a concrete form 105 for making curbs of various sizes that may

be readily adjusted, and while I have illustrated a curb using what is known as a button chain pump, my invention can be easily adjusted to chain pumps using elevator buckets. While I have shown a curb form made of sheet metal, I desire it to be known that wood or other suitable material may be used instead of sheet metal with slight variations that fall fully within the spirit of my invention.

The cistern curb to which my invention relates consists of a main body portion A, a cap B, a cistern cover C, an additional cover D for the opening in the cover C, of an endless chain E, and a rotatable wheel F, and a spout G.

In my preferred method of construction, a sheet metal cover 1 is formed in the shape desired for the body A of the curb. The sheet metal cover is preferably composed of two parts, which are longitudinally joined together by means of having their margins turned at right angles to form a suitable flange 2, said flange having perforations 3 at suitable distances apart and bolted together by bolts and wing nuts 4. Near the base of the curb, the cover is hinged at 5, which permits a lateral movement of the lower portion 6, which is secured at any particular angle by means of bolts and wing nuts, said bolts being passed through the holes in the under members, shown at 7 in Fig. V.

The purpose of this construction is to provide for adjustment to suit cisterns having different size openings in their covers. A plurality of Z-shaped members 8 are provided to hold the bottom part 9 of the form in position over the opening in the cistern. A U-shaped member 10 attached to the bottom part 9 of the form serves the purpose of holding a joint of pipe 11, screw-threaded at its lower end 12, in position while the concrete is being poured into the mold. A like section of pipe 13 is placed in position parallel with the pipe 11, which serves as a guideway for the return of the chain F.

When the form is properly adjusted and placed in position upon the cistern curb, a conventional type chain pump, consisting of an endless chain having rubber buttons spaced apart at suitable distances and caused to rotate perpendicularly by means of a sprocket wheel E and a suitable crank 14, is placed on top of the main body of the curb, in its natural position.

Before placing the sprocket wheel E and its axle 15 in position, a curvilinear form 16, substantially rectangular in cross-section, is placed in the center of the main body of the curb and held in position by the weight of the wheel and chain.

A similar curvilinear form 17 is provided in the top portion, or cap, B of the form, so that when the cap B is placed in position

and secured by the bolts and wing nuts 4, the form is ready to be filled with concrete.

A cast iron spout G is held in position by means of stud bolts 18 cast into the body of the concrete wall.

The form for the cover D, as shown in Figs. VII and VIII, may be made to suit any size opening by securing the blocks 19 at a proper distance apart upon the baseboard 20.

Having thus fully described my invention, what I claim as new and useful and desire to secure by Letters Patent is:

1. An adjustable form, or mold, for making concrete cistern curbs and covers, comprising a form, or mold, composed of two or more sections adapted to be detachably joined together in such a manner as to form a casing, the general contour of which is that of a conventional cistern curb, and having near its base a hinged portion adapted to be moved either outwardly or inwardly for the purpose of increasing or decreasing the area of the base of said curb, and having means for securing said hinged portion in predetermined positions, and having a plurality of Z-shaped members adapted to hold the bottom of said cistern mold in position over the opening into the cistern, as described and for the purposes set forth.

2. An adjustable form, or mold, for making concrete cistern curbs and covers, comprising a form, or mold, composed of two or more sections adapted to be detachably joined together in such a manner as to form a casing, the general contour of which is that of a conventional cistern curb, and having near its base a hinged portion adapted to be moved either outwardly or inwardly for the purpose of increasing or decreasing the area of the base of said curb, and having a plurality of Z-shaped members adapted to hold the bottom of said cistern mold in position over the opening in the cistern, said bottom being provided with a U-shaped member adapted to hold in position a section of threaded pipe, and having a curvilinear housing adapted to enclose a sprocket wheel and chain, thereby forming a recess in the concrete, in which said wheel and chain are adapted to rotate, as described and for the purposes set forth.

3. An adjustable form, or mold, for making cistern curbs, comprising a metal outer casing composed of two or more detachably joined sections, having their marginal edges flanged and turned at right angles to the main body of the mold and adapted to be bolted together by means of bolts and wing nuts and having adjacent to their base a hinged portion adapted to be adjusted outwardly or inwardly in order to cover openings of various sizes, and having means for holding said hinged portion in a plurality of predetermined positions, and having

means for closing the base of said form, or mold, and having a separate and independent mold for forming the cap or top of the cistern curb and having means for adjusting the mold to various size openings, as described and for the purposes set forth.

In witness whereof I have hereunto af-

fixed my signature this 17th day of July, 1924, in the presence of two witnesses.

CONSTANTIN F. GRETZMACHER.
